CLAIM

We claim the ornamental design for a glove, as shown and described.

DESCRIPTION

The file of this patent document contains at least one drawing executed in color. Copies of this patent document with color drawings will be provided by the United States Patent and Trademark Office upon request and payment of the necessary fee.

FIG. 1 is a top and left perspective view of a right hand glove according to a first embodiment.

FIG. 2 is a top view of the right hand glove of FIG. 1.

FIG. 3 is a left side view of the right hand glove of FIG. 1.

FIG. 4 is a right side view of the right hand glove of FIG. 1.

FIG. 5 is a front view of the right hand glove of FIG. 1.

FIG. 6 is a top and right perspective view of a left hand glove mirroring the right hand glove of FIG. 1.

FIG. 7 is a top view of the left hand glove of FIG. 6.

FIG. 8 is a right side view of the left hand glove of FIG. 6.

FIG. 9 is a left side view of the left hand glove of FIG. 6.

FIG. 10 is a front view of the left hand glove of FIG. 6.

FIG. 11 is a top and left perspective view of a right hand glove according to a second embodiment illustrated in color.

FIG. 12 is a top view of the right hand glove of FIG. 11.

FIG. 13 is a left side view of the right hand glove of FIG. 11.

FIG. 14 is a right side view of the right hand glove of FIG. 11.

FIG. 15 is a front view of the right hand glove of FIG. 11.

FIG. 16 is a top and right perspective view of a left hand glove mirroring the right hand glove of FIG. 11 illustrated in color.

FIG. 17 is a top view of the left hand glove of FIG. 16.

FIG. 18 is a right side view of the left hand glove of FIG. 16.

FIG. 19 is a left side view of the left hand glove of FIG. 16; and,

FIG. 20 is a front view of the left hand glove of FIG. 16.

Any portion of the glove shown in broken lines is included for the purpose of illustrating environment and forms no part of the claimed design.
